CLAIM

The ornamental design for a display screen or portion thereof with graphical user interface, as shown and described.

DESCRIPTION

The FIGURE is a front view of a display screen or portion thereof with graphical user interface, showing our new design.

Broken lines in the drawings denote features of the article that are included for the purpose of illustrating context, but form no part of the claimed design.

The outermost broken lines illustrating a display screen or portion thereof with graphical user interface form no part of the claimed design. The remaining broken lines illustrating portions of the graphical user interface form no part of the claimed design.
